FUEL SUPPLYING APPARATUS

Johnny W. Fyksen, Rawlins, Wyo.

Application August 5, 1941, Serial No. 405,542

5 Claims. (Cl. 48-3)

This invention relates to generally heating torches, and has as an object to provide a torch of the acetylene type, in connection with which means is provided for enriching the gaseous mixture for the torch with gasoline or kindred volatile fuel.

It is also an object of the invention to provide a torch of this kind which is portable in character and which can be employed with particular advantage in welding.

The invention consists in the details of construction and in the combination and arrangement of the several parts of my improved heating torch whereby certain important advantages are attained, as will be hereinafter more fully set forth.

In order that my invention may be the better understood, I will now proceed to describe the same with reference to the accompanying drawing, wherein:

Figure 1 is a view in elevation, with portions broken away, of a heating torch constructed in accordance with an embodiment of my invention;

Figure 2 is an enlarged fragmentary view, partly in section and partly in elevation, particularly illustrating the means herein comprised for mixing a volatile fuel with the acetylene gas; and

Figure 3 is a detailed sectional view of the jet taken substantially on the line 3-3 of Figure 1.

As disclosed in the accompanying drawing, 1 denotes a tank or reservoir of desired dimensions and preferably of a five gallon capacity, although it is not desired to limit the invention in this respect. The wall of this tank or reservoir 1 carries, at a desired point, a conventional valve controlled filling stem 2 to provide means whereby water or air may be forced within the tank or reservoir 1 as desired.

The top wall 3 of the tank or reservoir 1 is provided with a relatively large opening 4 which is normally closed by a plug 5, or otherwise as may be preferred. This opening 4 constitutes an entrance whereby carbide may be placed within the tank or reservoir 1 as required.

In communication with and extending laterally from the upper portion of the reservoir or tank 1, and supported by the wall thereof, is a carry-off pipe 6, the flow through which being under control of a conventional valve 7. The pipe 6, at a point between the tank or reservoir 1 and the valve 7, has in communication therewith a gauge 8 whereby the pressure of the gas gener-

ated within the tank or reservoir 1 may be readily and conveniently determined.

The bore 9 of the carry-off pipe 6 delivers within the upper portion of a container 10 of suitable dimensions and which is preferably of glass, although it is to be understood that the invention is not to be limited to any particular material. Depending from the bottom wall of this container 10 is an outlet nipple 11, the flow through which is under control of a conventional valve 12.

Extending upwardly from the pipe 6 is an up-standing discharge pipe 14 for the fuel mixer. Within the upper portion of the container 10 is a suction tube 15 having its inserted end portion disposed downwardly, as at 16, within the container 10 to extend below the level of the gasoline within the container 10. This tube 15 is continued by a port 17 which communicates with the bores 18 of the discharge pipe 14. The wall of the tube 15, at the top of the depending portion 16, is provided with an opening 19. The flow out through the tube 15 to the port 17 of the pipe 14 is under control of a conventional valve 20.

Carried by the upper end of the discharge pipe 14 is a hollow spherical member 21 providing a chamber which serves to catch any overflow or excess gasoline. The member 21 is provided with a discharge nipple 22 to which is coupled an angular pipe fixture 23. Leading from this fixture 23 is a flexible hose 24 provided at its outer end with a jet nozzle 25, said nozzle 25 being formed to provide a hand hold 26. With the valves 7 and 20 open the acetylene gas generated within the tank or reservoir 1 will pass through the bore of the pipe 6 into the container 10 and through the opening 19 into the port 17 and out through the pipe 14 and its associated parts to the jet nozzle 25. This travel of the acetylene gas will also result in drawing up through the depending portion 16 of the suction tube 15 a certain amount of the gasoline or kindred volatile liquid within the container 10, and thereby materially enriching the fuel when delivered to the jet nozzle 25, thus assuring an effective flame.

From the foregoing description it is thought to be obvious that a heating torch constructed in accordance with my invention is particularly well adapted for use by reason of the convenience and facility with which it may be assembled and operated.

I claim:

1. Apparatus for supplying fuel to a burner, comprising a tank for fuel gas under pressure, an auxiliary fuel tank in which liquid fuel is main-

tailed at a predetermined level, means for conducting gas under pressure from the first tank into the auxiliary tank above said level, a suction tube disposed vertically in the auxiliary tank and having one open end near the bottom of the auxiliary tank and leading out therefrom above the fuel level, means connected with the other end of said tube for conducting fuel to the burner, and an inlet opening in the tube above the liquid level by which the fuel gas under pressure may pass into said conducting means.

2. Apparatus for supplying fuel to a burner, comprising a tank for fuel gas under pressure, an auxiliary fuel tank in which liquid fuel is maintained at a predetermined level, means for conducting gas under pressure from the first tank into the auxiliary tank above said level, a suction tube disposed vertically in the auxiliary tank and having a portion opening at one end near the bottom of the tank and having a portion of its other end extending laterally through the wall of the auxiliary tank, pipe means connected with the said other end of the tube for conducting fuel to the burner, and the wall of the tube having an opening therein in a position to admit fuel gas under pressure from the upper part of the auxiliary tank at the angle between the two portions of the tube and in line with the second portion of the tube, whereby to create a suction effect through the first mentioned portion of the tube to draw liquid fuel therethrough and into the fuel conducting means.

3. Apparatus for supplying fuel to a burner, comprising a tank designed to contain fuel gas under pressure, an auxiliary tank designed to contain a liquid fuel at a prescribed level, a coupling member between the two tanks and having two passages therein, each passage leading at one end into the auxiliary tank above said level, one passage leading from the gas tank and the other passage opening laterally through said coupling member, a suction tube in the auxiliary tank and having two right angularly related portions, one of said tube portions being connected in the said other passage and the other portion extending downwardly into the tank to a point adjacent the bottom thereof, tubular means connected to the lateral opening end of said other passage for conducting fuel to the burner, and said suction tube having an opening therein in the convex side of the angle between the two portions thereof for admitting gas into and substantially on the axis line of the said one of the tube portions.

4. Apparatus as set forth in claim 3, in which the said tubular means has a portion extending vertically from the coupling member and includes as a part of its structure a globe designed to receive liquid fuel which may be drawn into the tubular means to prevent passage of such liquid fuel to the burner.

5. Apparatus as set forth in claim 3, and with a shut-off valve in each of said two passages for controlling the flow of fuel therethrough.

JOHNNY W. FYKSEN.
